US0D1077444S

(12) **United States Design Patent** (10) **Patent No.:** **US D1,077,444 S**
(45) **Date of Patent:** **** Jun. 3, 2025**

(54) **SHOE SOLE**(71) Applicant: **PUMA SE**, Herzogenaurach (DE)(72) Inventors: **Arnaud Redon**, Nuremberg (DE);
Christopher Dunning, Herzogenaurach (DE)(73) Assignee: **PUMA SE**, Herzogenaurach (DE)(***) Term: **15 Years**(21) Appl. No.: **29/979,922**(22) Filed: **Dec. 20, 2024****Related U.S. Application Data**

(63) Continuation of application No. 18/822,894, filed on Sep. 3, 2024, which is a continuation of application No. 18/651,163, filed on Apr. 30, 2024, now Pat. No. 12,096,825, which is a continuation of application No. 18/505,674, filed on Nov. 9, 2023, which is a continuation of application No. 17/396,912, filed on Aug. 9, 2021, now Pat. No. 11,819,088.

(57)

CLAIM

The ornamental design for a shoe sole, as shown and described.

DESCRIPTION

The sole FIGURE is a bottom plan view of an ornamental design for a shoe sole.

The dash-dash-dash lines are included for the purpose of illustrating portions of the shoe sole that form no part of the claimed design. The surfaces between the lines are not claimed.
